UNITED STATES PATENT OFFICE.

GEORGE W. CURTIS, OF MILWAUKEE, WISCONSIN, ASSIGNOR TO THE TIMKEN ROLLER BEARING COMPANY, OF CANTON, OHIO, A CORPORATION OF OHIO.

DREDGE HEAD.

Application filed September 9, 1927. Serial No. 218,463.

My invention relates to dredge heads and the like and particularly to the mounting of the rotary shaft that carries the cutter head; and it has for its principal object a mounting 5 in which the shaft is supported in roller bearings and in which the bearings are entirely protected from water and grit. Dredge heads that operate under water to loosen gravel and the like by means of rotary cutters and then 10 remove the gravel to the surface of the water by means of a suction pump offer a very difficult problem in the mounting of the cutter head shaft. If anti-friction bearings are used, it is very difficult to protect the bearings 15 from water and grit. The present invention consists in providing the ends of the housing in which the shaft is mounted with a plurality of closure disks and with springs for holding them in contact with each other, the closing 20 disks being free to yield to maintain close contact. The invention further consists in the dredge head and in the parts and combinations and arrangements of parts hereinafter described and claimed.

25 In the accompanying drawing which forms part of this specification and wherein like reference numerals indicate like parts wherever they occur,

Fig. 1 is a longitudinal sectional view of a 30 dredge head mechanism embodying my invention,

Fig. 2 is a cross sectional view on the line 2—2 of Fig. 1;

Fig. 3 is a fragmentary sectional view similar to Fig. 1 on an enlarged scale and also showing a slightly modified form of the invention, and

40 Figs. 4 and 5 are views of disks at the left hand side of the bearing tending to force oil outwardly and inwardly, respectively.

The shaft 1 on which the cutter head is mounted is disposed in a housing 2. In the form shown in Figs. 1 and 2 the interior of said housing is reduced in diameter at one end

45 3. Mounted in said housing 2 is a hollow shell 4 that has an enlarged middle portion 5 disposed in the enlarged portion of the interior of the housing. After the shell 4 has been

50 inserted in the housing 2 a metal ring or spacer 6 is mounted in the end of the housing, forming a reduced bore similar to the reduced bore 3 at the other end of the housing. The enlarged portion 5 of the shell 4 is preferably convexly curved endwise of the shell so as to 55 permit it to rock in the housing 2. The shell 4

is held in the housing by means of bolts 7 that extend through the housing into holes 8 provided therefor in the shell, said holes being larger than said bolts.

The shaft 1 is provided with a reduced 60 portion 9 on which is mounted a split collar 10 that serves as an abutment for the cones 11 or inner bearing members of conical roller bearings. The shell 4 is provided with an integral flange 12 at one end and a ring 13 65 is threaded into the other end of said shell to close the same. The cups 14 or outer bearing members are mounted in the shell abutting against said end flange 12 and said ring 13 respectively. Conical rollers 15 are inter- 70 posed between the cups 14 and cones 11 and are preferably provided with suitable cages 16.

Sleeves 17 are mounted on the shaft 1 to abut against the bearing cones 11. Each 75 sleeve 7 is provided with an upstanding annular rib 18. In order to prevent water and grit from entering into the housing 2 and the shell 4 that carries the bearings, a plurality 80 of perforated disks are provided. Preferably these disks are arranged in groups or sets of three, each set comprising two metal disks secured to an intermediate disk of leather or other yieldable or flexible material, the metals being selected so that two different metals 85 will rub against each other, thus minimizing friction; some sets (indicated generally by the numeral 19 at the right of Fig. 1) being arranged to rotate with the shaft and alternating sets (indicated generally by the numeral 20 at the right of Fig. 1) being fixed in the housing.

In the particular form shown in the drawings, the outermost set comprises two bronze disks 21 and an intermediate leather disk 95 22. The leather disk 22 is secured to the rib 18 of the sleeve 17 as by a rivet 23 that extends through the rib and also secures the leather disk 22 of the third set of disks to the other side of the rib. The disks of each 100 set are secured to each other as by countersunk pins 24 or rivets.

An end ring 25 and a cap 26 are secured to each end of the housing as by bolts. Interposed between each ring 25 and the end of 105 the housing 2 and between each cap 26 and ring 25 are leather disks 27. On either side of each leather disk 27 are steel disks 28 that are secured thereto as by countersunk rivets or pins 29. Thus, in the embodiment shown 110

in the drawings, the two sets of bronze disks 21 with their intermediate leather disks 22 rotate with the shaft and the two sets of steel disks 28 with their intermediate leather disks 27 are secured in the housing. Mounted in the end flange 12 of the shell 4 and in the end ring 13 are springs 30 that bear against the adjacent innermost friction disk (as 28). These springs 30 hold the sets of disks 19, 20 in close contact with each other, the leather disks 22, 27 being able to yield as required. Mounted in the end of each cap are a suitable packing 31 and gland 32.

Preferably the housing 2, rings 25 and caps 26 are provided with alining longitudinal passageways 33 for lubricant, the passageways of the cap opening into transverse passageways 34 that open into the end portions of the interior of the housing adjacent to the outer peripheries of the disks that rotate with the shaft. Suitable plugs 35 are provided for closing the outer openings to these passageways except when lubricant is to be admitted. The housing 2 and shell 4 may be provided with transverse passageways 36 permitting lubricant to be introduced into the interior of the shell in which the bearings are mounted.

In the slightly modified form of the invention shown in Fig. 3, the ends 41 of the shell 4^a fit snugly in the ends 42 of the housing 2^a, the middle portions being cut away so as to be spaced apart slightly, thus reducing the finishing work required. This construction does not permit the self-alinement of the shell that is permitted by the other construction.

To further assist in keeping water and grit out of the enclosure, thus protecting the disks as well as the bearings, some of the disks may be provided with spiral grooves that tend to force the lubricant through a labyrinthine path, as indicated by arrows in Fig. 3. A certain amount of oil will creep along the sleeve 17 over the ends of the set of steel disks 28 nearest the bearing 15. The adjacent bronze disk 21 is provided with spiral grooves that tend to force the oil outwardly. Oil creeping longitudinally of the housing over the ends of the disks 21, together with oil coming through the lubricant passageways of the housing is then forced inwardly by means of spiral grooves in the next bronze disk, thence it creeps along the rib 18 and is again forced outwardly by spiral grooves in the next bronze disk and again inwardly by grooves in the outermost bronze disk. Little, if any, oil escapes through the packing 31. The above described pumping of oil builds up an oil pressure to prevent ingress of water and grit and it lubricates the steel and bronze disks, thus prolonging their life. In Fig. 4 are shown spiral grooves 51 in the bronze disk nearest the bearing in Fig. 3, said grooves tending to force oil outwardly.

In Fig. 5 are shown spiral grooves in the outermost bronze disk tending to force oil inwardly. The necessary twist depends on the direction of rotation and other easily determinable factors.

The above described dredge head entirely prevents ingress of water and grit to the interior of the housing and to the bearings. At the same time the arrangement and construction of the disks minimize friction; and the bearings are capable of standing up under the heavy service required. The disks are free to yield as required and the shell in which the outer bearing members are mounted may be arranged so as to be capable of slight rocking or other alining movement. Obviously numerous changes might be made without departing from the invention and I do not wish to be limited to the precise construction shown.

What I claim is:

1. A construction of the kind described comprising a shaft, a housing therefor, roller bearings for said shaft, and a multiplicity of closure rings mounted in each end of the housing, said rings being arranged in sets of three, each set comprising a middle yieldable ring and rings on either side thereof and secured thereto.

2. A construction of the kind described comprising a shaft, a housing therefor, roller bearings for said shaft, and a multiplicity of closure rings mounted in each end of the housing, said rings being arranged in sets of three, each set comprising a middle yieldable ring and rings on either side thereof and secured thereto and contacting rings of adjacent sets being of different material.

3. A construction of the kind described comprising a housing, a shaft in said housing, conical roller bearings for said shaft, yieldable disks mounted to rotate with said shaft, bronze disks on each side of each yieldable disk and secured thereto, yieldable disks secured in the housing and steel disks on both sides of said yieldable disks and secured thereto.

4. A construction of the kind described comprising a housing, a shaft in said housing, conical roller bearings for said shaft, yieldable disks mounted to rotate with said shaft, bronze disks on each side of each yieldable disk and secured thereto, yieldable disks secured to the housing and steel disks on both sides of said yieldable disks and secured thereto, the bronze disk in each set that is nearest the bearing being provided with spiral grooves to force oil outwardly and the other bronze disk of each set being provided with spiral grooves to force oil inwardly.

5. A construction of the kind described comprising a housing, a shaft in said housing, a hollow shell in said housing, conical roller bearings interposed between said shell and said shaft, yieldable disks mounted to

rotate with said shaft, bronze disks on each side of each yieldable disk and secured thereto, yieldable disks secured in the housing, steel disks on both sides of said yieldable disks and secured thereto and springs mounted in the end of said shell and pressing against said disks to hold them in engagement with each other.

6. A construction of the kind described comprising a housing, a shaft in said housing, a hollow shell in said housing, conical roller bearings interposed between said shell and said shaft, yieldable disks mounted to rotate with said shaft, bronze disks on each side of each yieldable disk and secured thereto, yieldable disks secured in the housing, steel disks on both sides of said yieldable disks and secured thereto said housing having lubricant passageways terminating at the outer peripheries of said disks mounted to rotate with said shaft.

7. A construction of the kind described comprising a housing, a shaft in said housing, a hollow shell in said housing, conical roller bearings interposed between said shell and said shaft, yieldable disks mounted to rotate with said shaft, bronze disks on each side of each yieldable disk and secured thereto, yieldable disks secured in the housing, steel disks on both sides of said yieldable disks and secured thereto said housing and said shell having lubricant passageways admitting lubricant to the interior of said shell for said bearings.

8. A construction of the kind described comprising a housing, a shaft in said housing, a hollow shell in said housing, conical roller bearings interposed between said shell and said shaft, sleeves on said shaft abutting against the inner bearing members of said bearings, each sleeve being provided with an annular rib, yieldable disks secured to the sides of said ribs, bronze disks on each side of each yieldable disk and secured thereto, yieldable disks secured between the housing and the end rings and between the end rings and the end caps, steel disks on both sides of said yieldable disks and secured thereto and springs mounted in the ends of said shell and pressing against said disks to hold them in engagement with each other.

9. A construction of the kind described comprising a housing, a shaft in said housing, a hollow shell in said housing, conical roller bearings interposed between said shell and said shaft, sleeves on said shaft abutting against the inner bearing members of said bearings, each sleeve being provided with an annular rib, yieldable disks secured to the sides of said ribs, bronze disks on each side of each yieldable disk and secured thereto, yieldable disks secured in the housing, steel disks on both sides of said yieldable disks and secured thereto and springs mounted in the ends of said shell and pressing against

said disks to hold them in engagement with each other.

10. A construction of the kind described comprising a housing, end rings, end caps, means for securing said housing, rings and caps together, a shaft in said housing, a hollow shell in said housing, conical roller bearings interposed between said shell and said shaft, sleeves on said shaft abutting against the inner bearing members of said bearings, each sleeve being provided with an annular rib, yieldable disks secured to the sides of said ribs, bronze disks on each side of each yieldable disk and secured thereto, yieldable disks secured between the housing and the end rings and between the end rings and the end caps, steel disks on both sides of said yieldable disks and secured thereto and springs mounted in the ends of said shell and pressing against said disks to hold them in engagement with each other.

11. A construction of the kind described comprising a housing, end rings, end caps, means for securing said housing, rings and caps together, yieldable disks in said housing having their peripheral portions held between said housing and said end rings and between said end rings and said caps respectively, metal disks on both sides of said yieldable disks and secured thereto, a shaft in said housing, yieldable disks mounted to turn with said shaft, and disks of different metal from said above mentioned metal disks secured to both sides of said yieldable disks.

12. A construction of the kind described comprising a housing, end rings, end caps, means for securing said housing, rings and caps together, yieldable disks in said housing having their peripheral portions held between said housing and said end rings and between said end rings and said caps respectively, metal disks on both sides of said yieldable disks and secured thereto, a shaft in said housing, yieldable disks mounted to turn with said shaft, disks of different metal from said above mentioned metal disks secured to both sides of said yieldable disks and springs pressing against the endmost disk.

13. A construction of the kind described comprising a housing, end rings, end caps, means for securing said housing, rings and caps together, yieldable disks in said housing having their peripheral portions held between said housing and said end rings and between said end rings and said caps respectively, metal disks on both sides of said yieldable disks and secured thereto, a shaft in said housing, yieldable disks mounted to turn with said shaft, and disks of different metal from said above mentioned metal disks secured to both sides of said yieldable disks, said housing having lubricant passageways terminating at the outer peripheries of said disks that turn with said shaft.

14. A construction of the kind described

comprising a housing, end rings, end caps, means for securing said housing, rings and caps together, yieldable disks in said housing having their peripheral portions held between said housing and said end rings and between said end rings and said caps respectively, steel disks on both sides of said yieldable disks and secured thereto, a shaft in said housing, yieldable disks mounted to turn with said shaft, and bronze disks secured to both sides of said yieldable disks.

15. A construction of the kind described comprising a housing, end rings, end caps, means for securing said housing, rings and caps together, yieldable disks in said housing having their peripheral portions held between said housing and said end rings and between said end rings and said caps respectively, steel disks on both sides of said yieldable disks and secured thereto, a shaft in said housing, yieldable disks mounted to turn with said shaft, bronze disks secured to both sides of said yieldable disks and springs pressing against the endmost disk.

25. 16. A construction of the kind described comprising a housing, a hollow shell in said housing, said shell having an enlarged middle portion convexly curved endwise of the shell to permit the shell to rock in said housing, one end of the interior of the housing having a reduced inside diameter, a washer in the other end of said housing fitting around the end portion of said shell, said shell being provided with a recess, a bolt of smaller diameter than said recess secured in said housing and extending into said recess, a shaft extending through said shell and housing, said shaft having a reduced portion, a split collar mounted on said reduced portion of said shaft, bearing cones on said shaft abutting against said collar, bearing cups mounted in the ends of said shell, bearing rollers interposed between said cups and cones, sleeves on said shaft abutting against said bearing cones, and a plurality of disks in the space between said sleeve and said housing.

17. A construction of the kind described comprising a housing, a hollow shell in said housing, said shell having an enlarged middle portion convexly curved endwise of the shell to permit the shell to rock in said housing, one end of the interior of the housing having a reduced inside diameter, a washer in the other end of said housing fitting around the end portion of said shell, said shell being provided with a recess, a bolt of smaller diameter than said recess secured in said housing and extending into said recess, a shaft extending through said shell and housing, said shaft having a reduced portion, a split collar mounted on said reduced portion of said shaft, bearing cones on said shaft abutting against said collar, bearing cups mounted in the ends of said shell, bearing rollers interposed between said cups and cones, sleeves on

said shaft abutting against said bearing cones, a plurality of disks in the space between said sleeve and said housing and springs in the ends of said shell pressing against the adjacent disk.

18. A construction of the kind described comprising a housing, a hollow shell in said housing, said shell having an enlarged middle portion, one end of the interior of the housing having a reduced inside diameter, a washer in the other end of said housing fitting around the end portion of said shell, said shell being provided with a recess, a bolt of smaller diameter than said recess secured in said housing and extending into said recess, a shaft extending through said shell and housing, said shaft having a reduced portion, a split collar mounted on said reduced portion of said shaft, bearing cones on said shaft abutting against said collar, bearing cups mounted in the ends of said shell, bearing rollers interposed between said cups and cones, sleeves on said shaft abutting against said bearing cones, a plurality of disks in the space between said sleeve and said housing, and springs in the ends of said shell pressing against the adjacent disk.

19. A construction of the kind described comprising a housing, end rings, end caps, means for securing said housing, rings and caps together, a hollow shell in said housing, said shell having a raised middle portion convexly curved endwise of the shell to permit the shell to rock in said housing, one end of the interior of the housing having a reduced inside diameter, a washer in the other end of said housing fitting around the shell, said shell being provided with a recess, a bolt of smaller diameter than said recess secured in said housing and extending into said recess, a shaft extending through said shell and housing, said shaft having a reduced portion, a split collar mounted on said reduced portion of said shaft, bearing cones on said shaft abutting against said collar, bearing cups mounted in the ends of said shell, bearing rollers interposed between said cups and cones, sleeves on said shaft abutting against said bearing cones, a plurality of disks in the space between said sleeve and said housing and springs in the ends of said shell pressing against the adjacent disk.

20. A construction of the kind described comprising a housing, end rings, end caps, means for securing said housing, rings and caps together, a hollow shell in said housing, said shell having a raised middle portion convexly curved endwise of the shell to permit the shell to rock in said housing, one end of the interior of the housing having a reduced inside diameter, a washer in the other end of said housing fitting around the shell, said shell being provided with a recess, a bolt of smaller diameter than said recess secured in said housing and extending into said recess,

a shaft extending through said shell and housing, said shaft having a reduced portion, a split collar mounted on said reduced portion of said shaft, bearing cones on said shaft 5 abutting against said collar, bearing cups mounted in the ends of said shell, bearing rollers interposed between said cups and cones, and sleeves on said shaft abutting against said bearing cones, a plurality of 10 disks in the space between said sleeve and said housing, said disks being arranged in sets of three, each set comprising a yieldable disk and metal disks secured to both sides thereof, some of said sets being fixed in said housing and alternate sets being fixed to said 15 sleeves and contacting disks being of different metals, said housing being provided with lubricant passageways terminating adjacent to the disks that rotate with said shaft, and springs in the ends of said shell pressing 20 against the adjacent disk.

Signed at Milwaukee, Wisconsin, this 3rd day of September, 1927.

GEORGE W. CURTIS.
